UNITED STATES PATENT OFFICE.

WILLIAM J. CULLEN, OF JOLIET, ILLINOIS, ASSIGNEE TO AMERICAN CAN COMPANY, OF NEW YORK, N. Y., A CORPORATION OF NEW JERSEY.

CONTAINER-BODY.

1,299,824.

Specification of Letters Patent. Patented Apr. 8, 1919.

Application filed December 27, 1915. Serial No. 68,693.

To all whom it may concern:

Be it known that I, WILLIAM J. CULLEN, a citizen of the United States, residing in Joliet, in the county of Will and State of Illinois, have invented a new and useful Improvement in Container-Bodies, of which the following is a specification.

This invention relates in general to container bodies and has more particular reference to container or box bodies constructed of corrugated fiber board.

A principal object of the invention is the provision of a new and improved connection between adjacent edges of such material in a box or container body or part.

Prior to my invention it has been generally the custom, in constructing boxes or containers of various shapes and sizes of corrugated board, to bring the adjacent edges together and paste over them a cloth strip, one sometimes being pasted inside as well as outside. Another method of connecting the edges has been merely to overlap them and secure them in this position with an adhesive.

Containers and boxes of this character are now replacing wood and metal containers to a considerable extent. Heavy materials may be packaged in them, as the board itself is readily constructed of sufficient strength. The means of fastening the ends together have, in the past, possessed far less strength than the strength of the corrugated board itself, and it is an object of this invention to provide a connection for fastening the edges together, which will materially increase the strength of this connection and make it more nearly approximate the strength of the remainder of the package.

A further object of the invention is the provision of such a connection which will give to the box a pleasing and finished appearance, and this without the utilization of more material than has heretofore been required and also without increasing materially the cost of production.

Other objects and advantages of the invention will be apparent as it is better understood from the following description when considered in connection with the accompanying drawing illustrating a preferred embodiment thereof.

Referring to the drawing:

Figure 1 is a small perspective view of a box embodying my invention;

Fig. 2 is a larger view of the same box having the parts separated to show the construction; and

Fig. 3 is a partial enlarged section substantially in the plane 3-3 of Fig. 1.

The box shown on the drawing is of general rectangular form and of corrugated board; although it will be manifest, however, that it may have other forms and be constructed of other material. In the present instance the box is formed of a single sheet of material creased or scored transversely at 4 to define the side walls and provided with end flaps 5 adapted to constitute the ends of the box. Three corners of the box in the present instance are formed at the score lines, the blank or sheet being foldable on the score lines 4 to bring the box to the form shown in Fig. 2. The free vertical edges 6 and 7 are adapted to be connected together to finish the construction of the box, and it is in the connection of these edges that the present embodiment of my invention is found. One edge, 7, is extended beyond the superficial area of its adjacent wall 8 and is divided therefrom by a score line or crease 9. The central or corrugated ply 10 of the projecting edge thus formed is removed or eliminated to provide two spaced tongues 11 formed respectively of the inner and outer plies of material. The inner faces of these tongues, or upon the outer faces of the side 12 adjacent the edge 6, are provided with an adhesive and the edge 6 is inserted between the two tongues 11 which are pressed down and secured upon the faces of the side 12 near the edge 6 by the adhesive.

This provides a connection between the edges of the container or box of strength substantially equal to the strength of the board, and of strength much greater than that provided by securing the edges together with cloth.

It is thought that the invention and many of its attendant advantages will be understood from the foregoing description, and it will be manifest that various changes may be made in the form, construction and

material of the box and in the details of the connection between the edges without departing from the spirit and scope of the invention or sacrificing any of its material advantages, the form hereinbefore described being merely a preferred embodiment thereof.

I claim:

A joint for corrugated fiber board boxes, said board comprising two outer flat layers 10 and an intermediate corrugated layer, which consists of the united portions of two sections of said board one arranged within the other, the first section being a side of said box the corrugated layer of which is left intact, and

the second section being a bifurcated flap of 15 a contiguous side the corrugated layer of which is removed, the flat layers of which flap embrace the first section, and the flat layers of the second section being adhered directly to the faces of the flat layers of the 20 first section, both within the box and without the box.

Signed in the presence of two subscribing witnesses.

WILLIAM J. CULLEN.
